Specification for Design.

Patented Jan. 3, 1922.

Application filed November 8, 1919. Serial No. 336,756. Term of patent 14 years.

To all whom it may concern:

Be it known that I, JORGEN P. L. JORGENSEN, a citizen of the United States, residing at Omaha, in the county of Douglas and State of Nebraska, have invented a new, original, and ornamental Design for a Building Block, of which the following is a specification, reference being had to the accompanying drawing, forming a part thereof.

Figure 1 is a plan view of a building-block showing my new design. Fig. 2 is a front side view of the same. Fig. 3 is a rear side

view of the building-block. Fig. 4 is an end view of the building-block.

I claim:

The ornamental design for a building-block, as shown.

In testimony whereof, I have affixed my signature in presence of two witnesses.

JORGEN P. L. JORGENSEN.

Witnesses:

HIRAM A. STURGES,
